Des. 213,232
Patented Jan. 14, 1969

213,232

TYPEWRITER HOUSING

Carl Auboeck, Vienna, Austria, assignor to Olympia
Werke A.G., Wilhelmshaven, Germany

Filed Dec. 28, 1967, Ser. No. 9,963

Claims priority, application Germany Sept. 4, 1967

Term of patent 7 years

U.S. Cl. D64—11
Int. Cl. D18—01

Fig. 1

Fig. 2

Fig. 3

FIG. 1 is a perspective front view of a typewriter housing;

FIG. 2 is a perspective side view; and

FIG. 3 is a perspective rear view of my new design.
The broken line showing of the keys and other elements is merely for illustrative purposes.

I claim:

The ornamental design for a typewriter housing, substantially as shown and described.
